UNITED STATES PATENT OFFICE.

ROBERT H. READ, OF WASHINGTON, DISTRICT OF COLUMBIA, ASSIGNEE TO GENERAL ELECTRIC COMPANY, A CORPORATION OF NEW YORK.

SHEATHED HEATER-WIRE AND METHOD OF MAKING SAME.

1,233,808.

Specification of Letters Patent. Patented July 17, 1917.

Application filed July 30, 1914, Serial No. 854,100. Renewed June 9, 1917. Serial No. 178,394.

To all whom it may concern:

Be it known that I, ROBERT H. READ, a citizen of the United States, residing in Washington, the District of Columbia, have 5 invented new and useful Improvements in Sheathed Heater-Wires and Method of Making Same, of which the following is a specification.

This invention relates to resistance elements for electric heaters, rheostats or the like, the object being to produce an element that will have a large radiating or heat transmitting surface permitting a higher current density in the conductor than is usually possible with safety to the conductor, and therefore admitting a more rapid diffusion of heat by the translating device to which it is applied. I have heretofore described in prior applications devices of this 20 general character in which mineral powder or oxids were employed as insulation; the present improvements are designed to cheapen and improve the character of the product. Asbestos insulation may be applied as tape, as a braided or woven tube, as flock secured to a metal tape, or as cord wound in a plurality of layers; the interstices between the fibers, even when compacted, admit of the presence of air carrying 25 some moisture, which renders possible the breaking down of the insulation at lower voltages than would be the case if less air were present. One of the features of the present improvements is to more effectually 30 exclude air and moisture, and I effect this result by filling the pores of the asbestos with a mineral oxid, such as finely divided silica or alumina. This may be done mechanically by forcing finely divided mineral 35 powder into the pores of the asbestos, or chemically by soaking the asbestos in a soluble salt and precipitating by a reagent or by heat a mineral residue in the pores or interstices, then drying out the material, thereby 40 greatly reducing the porosity of the asbestos insulation and raising its rupture point. Other features of the invention consist in casting a seamless metallic sheath around the asbestos-covered wire and forming a 45 watertight seam of hard solder in a folded metal tape inclosing the asbestos.

The invention embodies a sheathed wire

or element and method and apparatus for making the same, and the several features of novelty will be particularly hereinafter 55 described and definitely pointed out in the annexed claims.

In the drawings, Figure 1 shows a wire covered with a plurality of layers of closely wound asbestos cord. Fig. 2 shows a method and apparatus for folding an asbestos-covered metal tape around a core-wire, and mechanically filling the pores with finely divided mineral insulating powder, and brazing the seam. Fig. 3 shows a method of 60 filling the pores of an asbestos covered wire chemically with silica powder. Fig. 4 shows means for continuously hard-soldering the seam of a metal tape folded to form a sheath around a resistance wire. Fig. 5 shows a method and apparatus for casting 65 a seamless metal casing or sheath around an asbestos-covered wire. Fig. 6 shows an insulated terminal for the sheathed element.

Referring in detail to the drawings, 1, Fig. 75 1, represents very much magnified a core-wire of any desired material or composition suitable for the work in hand, if for heating work it should have a high specific resistance; if for conducting work it should be of 80 high conducting material, such as copper. It should be selected of a proper gage for the current density it must carry. It is covered with one or more layers 2, 8 of closely wound asbestos cord. In my prior application #843,236, filed June 5, 1914, I described such a wire inclosed in a seamless metal sheath; to satisfactorily withstand commercial lighting voltages a thicker bed of insulation is required than is the case in my 85 present improvements, as the pores and interstices of the asbestos carry some moist air; I greatly reduce the possibility of entrance of such moist air by filling the pores or interstices with a mineral oxid before 90 inclosing the insulated wire in the metal sheath.

In Fig. 2 I show a mode of filling the pores mechanically. As here shown a metal tape 4, is provided with a superposed layer 100 of asbestos, preferably in the form of flock, 4^a, caused to adhere to the metal by a film of silicate of soda; a tape of asbestos might be fed over the metal tape without being

secured to its face; but in either case the metal and superposed asbestos are led to a tapering die 5 through which is simultaneously led a core-wire 6 fed accurately to 5 the center of the die, and as it moves forward with the metal tape it is surrounded with a tube of asbestos separating an outer cylindrical sheath which is gradually curled into cylindrical form by the flaring 10 die forcing the edges closely together in a seam which is maintained in a right line parallel to the axis by a knife blade of steel 7 fixed at the mouth of the die and projecting radially inward to intercept the 15 edges of the folded tape. A hopper containing finely divided mineral powder, such as ground flint, is jarred intermittently by a hammer, 9, operated by a continuously rotating actuator 10. The powder is thus 20 agitated and caused to feed uniformly as the wire and tape are led through the die and forms an evenly distributed annular layer around the wire and between it and the asbestos. As the parts are fed to the 25 right, the tape is closed into a tube with a closed seam, which is held from gaping open under heat, when soldered, by the die-pressure, and melted hard solder is applied from a small reservoir 11 supported on the 30 die and having an opening in the bottom so that the solder bathes the edges of the seam. The solder is maintained fluid by an insulated heater wire 12 supplied with current from any suitable source. The reservoir has heat insulating walls, 13, to conserve the heat, and the wire which forms the heater is embedded in insulation within the walls. The size of the wire is considerably magnified in the drawing; when it leaves 35 the die 5 it is inclosed in a metal sheath with a hard-soldered seam, and the asbestos is somewhat compacted and its interstices filled with finely divided mineral powder, while an annular layer of the powder lies 40 around the core-wire. The sheathed wire is then carried through smaller dies which reduce its cross-section and force more of the powder into the pores and interstices and further compact the asbestos until it is an 45 efficient thermal conductor which will carry away the heat from the core-wire and distribute it to any work to which the wire is applied by means of the inclosing metal sheath. A wire thus insulated carries very 50 little moist air, especially when the powder 8 with which the hopper is filled is brought hot from an oven where it is previously heated. Other oxids or insulating compounds which are heat-refractory insulators 55 may be used, as for example alumina, but finely divided flint is a desirable material as it is cheap, of high insulating value, highly heat refractory, and does not become 60 a conductor of the second class at high 65 temperatures.

In Fig. 3 I have shown a method of chemically filling the pores of the asbestos with finely divided powder. The treatment may be applied to the asbestos flock, cord, or tape in bulk before the asbestos is applied to the wire, but inasmuch as many high resistance alloys, such for example as nickel-chromium, nickel-manganese, etc., are not affected by weak acids the treatment may be applied after the wire is wound or 70 braided with asbestos and then led to the tanks of Fig. 3. It is guided over rollers in the tanks, as shown, passing first through a bath 14 containing a strong watery solution of suitable metal salt by which the 75 covering is soaked; it is then led through a second bath, 15, if the silicate is used, in which is contained a weak acid, for example hydrochloric acid, by which the silica is precipitated in the pores as a bulky pre- 80 cipitate of gelatinous silica; thence it may be passed through a bath of water in tank 16 in which the soluble chlorid is washed out, leaving pure gelatinous silica in the 85 pores and interstices. Thence it passes 90 through a tubular electric or other heater, 16^a in which the fiber and silica is dried, from which it emerges as an asbestos-covered wire filled with a dense deposit of finely divided dry silica of high insulating value. 95 Instead of treating with silicate of soda other minerals may be employed, for example a watery bath of ammonia alum may be used, and the soaked wire led through the drier and heater and raised to a red heat, which 100 will break up the salt and leave a deposit of finely divided alumina in the pores of the asbestos. Other salts might be used to leave a different deposit of insulating material 105 in the pores; I prefer the silica on account of its cheapness of production and its excellent thermal and insulating properties. The covered wire as thus treated may be passed through a die, Fig. 4 in which a metal tape 17 is fed and curled around the 110 asbestos-covered wire, a steel blade 7 being inserted radially in the mouth of the die to keep the seam straight, as in Fig. 2. A melting pot electrically heated and insulated against leakage of heat is mounted 115 over the die similarly to Fig. 2, the molten bath having access to the seam as indicated. The seam is held tightly closed and cannot gape open. If desired, the edges of the metal tape may have applied a suitable flux 120 before entering the die 5. When the wire leaves the die the seam is brazed or hard-soldered; it is then reduced in section in dies, rolls or a swaging machine in ordinary ways until the wire has the desired 125 fineness, when the insulation will be a hard, compact mass of good thermal and electrical insulating value. The brazing heat raises the wire to an annealing temperature and expels any air trapped in the asbestos and 130

silica. The seamed wire may be slipped into a loosely fitting seamless metal tube which can be then shrunk tight upon it by dies or other reducing means, and circuit 5 terminals made as hereinafter described.

In Fig. 5 I have illustrated a mode of casting a seamless sheath around the asbestos-covered wire. The covered wire 3 is led vertically between two grooved cast- 10 iron rolls 18, 18^a each of which has a semi-circular groove in its periphery. The rolls are hollow and provided with hollow trun- 15 nions mounted to turn in a support 19, and cold water or air is led through an induction pipe 20 fixed to the support 19, suitable packing being applied at the joint of the induction pipe with the tubular trunnions 21, 21^a. The inner end of the pipe 20 projects to the middle of the imaginary axis 20 of the hollow roll, its end being closed with a cap having four small jet-pipes 22 leading close to the wall of the grooved roll. Thus as the rolls are turned by suitable gearing, 25 cold air or water is led, as shown by the arrow *a* into the interior of the left-hand roll and discharged in four streams against its inner wall keeping it sufficiently cool to chill the fluid metal; the air or water is carried out through a hollow trunnion on the 30 front side of the left-hand roll and through a coupling to the front tubular trunnion of the right-hand roll, and thence by similar jet-pipes 23 is discharged against the wall of the right-hand roll from which it passes 35 out of the hollow trunnion on the rear of the right-hand roll to the eduction pipe 24. The metal, as for example low brass, is delivered from a melting pot 25 by a valve 26 in a small stream to a soapstone funnel 28, 40 which may be lined inside and outside with asbestos, through which it falls into the closed space between the asbestos-covered wire and the abutting edges of the semi-circularly grooved rolls; it is quickly chilled 45 by the relatively cool walls of the rolls, and this action is aided by the jets of cold air delivered upwardly in nozzles 27. The rolls may be superficially oxidized in the grooves 50 to more completely guard against adhesion of molten metal. The speed of the rolls will vary according to the specific heat and 55 thermal conductivity of the particular metal being cast; with very heavy metals of low specific heat the speed will be higher than with lighter metals, and the speed of travel is adjusted with reference to these characteristics of the metal used and the chilling effect of the rolls; as fast as the metal freezes 60 into a solid or pasty form it will leave the rolls and is thence delivered to any suitable reducing apparatus, such as rolls, dies, or a small swaging machine to compact the sheath on the asbestos. The proportions shown in Fig. 5 are much magnified as the 65 sheath is not more than from one thirty-

second to one sixty-fourth inch in thickness. The wire as thus described may be made of indefinite length from which any desired length may be cut off for use in translating devices. As the core wire is not reduced in 70 section, the reducing operations described serving only to compact the sheath into good thermal relation to the asbestos, the specific resistance of the original wire is the same; therefore it may be accurately predetermined and the length needed for any use 75 ascertained.

In Fig. 6 I have shown a terminal connection for the wire. When completed the wire is gripped in a hollow chuck with a tubular handle, somewhat like a pin-vise, and a circular knife revolved around it until the sheath is severed. The section of sheath cut off and the asbestos are stripped off at each 80 end of the element and a copper tube 29 adapted just to fit the core-wire is slipped over its exposed part at each end of the element; a copper wire 30 to form a lead wire to a binding post or circuit-terminal is then 85 inserted in the end of the copper tube and a steel countersink is struck with a hammer to indent the tube at two points 31 to interlock mechanically the tube and the core-wire. The upset metal forms an effective joint 90 which maintains good thermal relation and prevents accidental detachment of the lead. A piece of braided asbestos tubing 32 is then slipped over the joint and a tubular copper cap 33 pushed over the asbestos and over the end of the sheath. The joint with 95 the sheath is brazed as at 35 and fireproof cement applied around the end of the copper lead against the flange and the asbestos. The cement applied at 34 should be of a kind which will harden under heat, should be fire- 100 proof and should not have much shrinkage; I have found a paste made of powdered flint and a weak solution of silica of soda very effective; it adheres tenaciously to the parts, and when hardened in a small flame is converted into strong stone and is water and 105 fireproof.

Having thus described my invention what I claim as new and desire to secure by Letters-Patent is:—

1. A sheathed wire consisting of an interior conductor, a bed of heat refractory insulation around the conductor, and a metallic sheath around the insulation, the pores of the insulation being filled with a heat-re- 115 fractory finely divided material.

2. A sheathed wire consisting of an interior conductor, a bed of asbestos around the conductor having its pores filled with finely divided mineral insulation, and a metallic sheath around the asbestos in good 125 thermal relation to the conductor.

3. A sheathed wire consisting of an interior conductor, a bed of asbestos around the conductor having its pores filled with 130

finely divided mineral insulation, and a seamless metallic sheath around the asbestos in good thermal relation to the conductor.

4. A sheathed wire consisting of an interior conductor, a bed of asbestos around the conductor, and a bed of mineral insulation between the conductor and the asbestos.

5. A sheathed wire consisting of an interior conductor, a bed of heat-refractory insulation around the same, a metallic sheath embracing the insulation in good thermal relation to the conductor, and a terminal joint within the insulation consisting of a metal tube mechanically interlocked with the core and a good conducting lead wire projecting from the ends of the sheathed wire.

6. A sheathed wire consisting of an interior conductor, a bed of heat refractory insulation around the same, a metallic sheath inclosing the insulation in good thermal relation to the conductor, a terminal joint within the insulation consisting of a metal tube mechanically interlocked with the conductor, and a good conducting lead wire, and a metallic cap of good heat radiating capacity surrounding the joint and secured to the sheath.

7. The process of making a sheathed resistance element, consisting in covering the conductor with asbestos insulation, and introducing into the pores of the asbestos finely divided mineral insulation.

8. The process of making a sheathed resistance element consisting in covering the conductor with a surrounding bed of asbestos, and depositing in the pores of the asbestos fireproof insulating powder.

9. The process of making a sheathed resistance element, consisting in covering a conductor with a surrounding bed of asbestos, and precipitating within the pores of the asbestos heat-refractory insulating powder.

10. The process of making a sheathed resistance element, consisting in covering a conductor with a surrounding bed of asbestos, filling the pores of the asbestos with

a heat refractory insulating powder, and surrounding the insulation with a metallic sheath.

11. The process of making a sheathed resistance element, consisting in covering the conductor with a surrounding bed of asbestos, filling the pores of the asbestos with a heat-refractory insulating powder, and casting a seamless metallic sheath around the asbestos.

12. The process of making a sheathed resistance element, consisting in covering the conductor with a surrounding bed of asbestos, filling the pores of the asbestos with a heat refractory insulating powder, feeding the conductor progressively through an orifice, supplying molten metal to the orifice, and chilling the metal in the opening, whereby a seamless metallic sheath is cast around the asbestos.

13. The process of making a sheathed resistance element, consisting in covering the conductor with a surrounding bed of insulation, feeding it through an opening, supplying molten metal, and chilling the metal until solidified within the opening, whereby a seamless metallic sheath is cast around the insulation, and reducing the section of the cast sheath.

14. The method of making a sheathed seamed resistance element, consisting in passing a conductor covered with fireproof insulation through an opening which holds contracted the seam, and applying fluid metal continuously to the seam.

15. The method of making a sheathed resistance element, consisting in leading an asbestos-covered wire through rotating semi-circular walls, supplying molten metal, and chilling the walls continuously while the conductor passes, thereby solidifying a seamless metallic sheath around the conductor.
